EDWIN COWLES, OF CLEVELAND, OHIO.

Letters Patent No. 94,081, dated August 24, 1869.

IMPROVEMENT IN RAILROAD-CONDUCTORS' TICKET-BOX AND FARE-DETECTOR.

The Schedule referred to in these Letters Patent and making part of the same.

To all whom it may concern:

Be it known that I, EDWIN COWLES, of Cleveland, in the county of Cuyahoga, and State of Ohio, have invented a new and improved Portable Ticket-Case and Fare-Detector; and I do hereby declare that the following is a full, clear, and exact description thereof, reference being had to the accompanying drawings, making part of this specification, in which—

Figure 1, plate 1, is a perspective view of the improved case and detector complete, exposing the side from which the tickets are removed.

Figure 2, plate 1, is a section, taken longitudinally through the case and detector, in the plane indicated by line *z*, fig. 3.

Figure 3, plate 1, is a section through the case and detector, taken in the plane indicated by red line *x* in fig. 2.

Figure 4, plate 2, is a section through the cancelling and dating-devices, and through the receptacle for the pieces punched or cut from the tickets.

Figure 5, plate 2, is a section, taken transversely through the ticket-case, in the plane indicated by line *y* in fig. 2.

Figure 6, plate 2, is an enlarged end view of the cancelling and dating-devices.

Figures 7, 8, and 9, plate 2, are views of plates, which are applied to the piles of tickets when confined in the cells of the case.

Figure 10, plate 2, is an end-view of the tubular receptacle for containing the punchings of the tickets.

Figure 11, plate 2, is an inside view of the seal-plate for said tubular receptacle.

Similar letters of reference indicate corresponding parts in the several figures.

The primary object of this invention is to protect railroad companies and others interested in the conveyance of persons from one part of the country to another, by compelling conductors to make correct returns for the money which they collect from passengers.

The nature of my invention consists—

First, in a portable cellular ticket-case, which is adapted for containing, under lock, all the different kinds of tickets required for stations upon a railroad, and which is provided with a cancelling-punch and a dating-stamp, applied on one end of a tubular receptacle, which will receive the punchings, and indicate to the proper officer the number of tickets punched, their date and value, as will be hereinafter explained.

Secondly, in a portable cellular ticket-case, which is provided with an arm-ring and also a receptacle for the punchings of the tickets, which latter is arranged in such relation to the said arm-ring as to serve the purpose of a convenient handle for holding the case in

position upon the arm with one hand, while withdrawing the tickets and cancelling them with the other hand, as will be hereinafter explained.

Thirdly, in a cancelling-punch, in combination with a receptacle for the punchings, and also with a safety-lock, said parts being constructed in such manner as to prevent the removal of the punchings from their receptacle without detection, as will be hereinafter explained.

Fourthly, in combining a spring division-slide with the receptacle for the punchings of the tickets, in such manner as to enable a conductor to separate the punchings collected from tickets that are sold while travelling in one direction over the road, from those collected on the return trip, as will be hereinafter explained.

Fifthly, in a ticket-case, which is subdivided into a number of cells, for containing tickets representing different fares or values, and which is provided on one side with a slotted face, through which the tickets can be removed, one at a time, and on the opposite side with a removable back, for allowing the insertion of the tickets into their respective cells, which back is provided with a suitable lock, for preventing access to the tickets in this direction, except by an officer appointed for the purpose, as will be hereinafter explained.

Sixthly, in a sliding ticket-extractor, which is constructed so that one ticket only can be withdrawn from a cell at a time, and so that a ticket cannot be returned to its place in a cell after it is once drawn, except by the key-holder of the case, as will be hereinafter explained.

Seventhly, in a ribbed back plate to the case, in combination with an extracting slide, whereby the hooked end of the said slide can be returned to a position for taking a succeeding ticket after the withdrawal of a ticket from its receptacle, as will be hereinafter explained.

To enable others skilled in the art to understand my invention, I will describe its construction and operation.

In the accompanying drawings—

A represents a rectangular case or box, which may be made of thin metal, to afford lightness, and which has its front side *A'* made up of narrow strips, with spaces *b* between them, and its opposite side *B* hinged at *h*, and provided with a suitable lock, *L*, for allowing access to the interior of the case by the person holding the key of this lock.

The flange *a*, which surrounds the front side *A'* of the case, projects from the side far enough to serve as a guard for the exposed ends *c* of extractors *J*, projecting through slots or spaces *b*, as shown in fig. 1.

The back plate *B* has a ring, *C*, secured centrally

to it, through which the arm of the person carrying the case is passed, and by means of which such person will have both hands free.

From one end of the case A, a tube, D, extends horizontally, which tube is rigidly secured to the case, and has rigidly secured to its outer end, at right angles to it, a tube, E, as shown in figs. 1 and 2.

These two tubes, thus arranged, form a T-shaped handle, and are grasped by the hand on the arm, which is passed through the ring C, when the conductor desires to hold the case in a position for drawing tickets from the face A'.

The said tubes also serve other purposes, which will be hereinafter explained.

The interior of the case A is subdivided into separate chambers or cells, corresponding in number and capacity to the different kinds and sizes of tickets which it is desired the case should contain at any one time.

The depth or length of the cells is less than the thickness of the case and length of the tickets, so that when cover B is shut, a space, N, will be left between the rear ends of the cells and said cover.

The upper side of the bottom of each cell or horizontal row of cells, is in the plane of the slot b of such cell or row of cells, as shown in figs. 2 and 5, and at the front passage b of each cell, a stop, e, is formed, which is designed for preventing the ticket-extractor J of such cell being drawn out further than is necessary to expose the ends of the tickets to be taken by the fingers.

By making the cells shorter than the tickets which they are designed to receive, it will be seen that a sufficient length of the tickets will be exposed at the back of the cells to grasp them, and thus allow their ready removal by the proper officer when the cover B is off.

By printing or engraving, in any suitable manner, upon that portion of the face of the plate A, closing the front end of each cell, such numbers, letters, or other characters as will indicate the kind of ticket in such cell, the required ticket or tickets can be drawn with great facility, and by the exercise of a little care on the part of a conductor, he will not be likely to draw wrong tickets.

Each cell is provided with an extractor, J, and a follower, K, between which the pile or pack of tickets is confined by a spring, p, interposed between follower K and the top of its cell.

The extractor J is constructed with a narrow finger-piece, c, and bevelled-edge tines c² c³ on its front end, and with hooks c¹ c⁴ on its rear end, together with a notch or space, c², in this end.

The finger-piece c projects through the slot b of its cell, and the tines c² c³ are located in rear of the stop e, on the bottom of such cell, so that while a ticket, lying next to the extractor J, can be drawn from the bottom of its pile, between the said stop and the lower edge of the strip which covers the cell, still the extractor cannot be drawn entirely out of its cell, because the points of the tines c² c³ will be brought against the stop, and would curl up and be broken by its forcible withdrawal, which would expose an attempt at fraud.

The two tines, c¹, curve upwardly, and will resist an attempt to insert a ticket into a cell through the slot b of such cell, as indicated by fig. 9, in which the red lines are supposed to be a ticket.

The rear end of each extractor J is turned up nearly the thickness of a ticket, for the purpose of allowing the tickets to be drawn one at a time from a cell, and the rear end of each extractor is notched, at c², for the purpose of allowing the hooks or turned-up portions c¹ c⁴ to be moved back of the rear ends of the tickets when arranged in their cells, as shown in two instances in fig. 5.

The rear ends of the tickets in the several piles, abut against ribs r r, which are formed on the inner

side of the cover B, which ribs prevent the tickets from abutting against this side of the cover; and by reason of the notches c², in the rear ends of the extractors J, the hooked portions c¹ c⁴ are allowed to pass back of the tickets, as shown in fig. 3.

The tube E is separated into two apartments by a division-plate, d³, applied at the middle of its length, as shown in figs. 2, 3, and 4.

This plate d³ is on the end of the rod d¹, which is arranged in the tube D, and which is acted upon by a spring, d², that keeps the plate d³ in the position indicated in figs. 2 and 3.

By means of thumb-piece d, the division d³ can be moved back, and anything which was above this division, allowed to drop into the lower portion of the receptacle or tube.

A collar, f, is formed on the lower end of tube E, which is notched through its flanged end, as shown in fig. 10, for receiving hooks or slotted tongues g, formed on one side of a cap, g. A spring-catch, s²; and a stop, V, are arranged in the annular groove in said collar f, for catching and holding one of the said hooks g, and thus locking the cap g in place, as shown in fig. 2.

By means of a suitable key, inserted through a hole made through cap g, the spring-catch s² can be pressed to one side, and the cap removed by a quarter turn.

A plate, v, perforated to receive through it the three hooks, g, as shown in fig. 11, may be used for confining between it and cap g, a piece of paper, or other substance, which would cover the key-hole, and be broken by the insertion of the key or other instrument.

I do not confine myself to this construction of seal-lock, as other well-known locks may be used in its stead.

I, however, prefer to use this kind of lock, because of its simplicity and security.

Upon the upper end of the tube E, a punch-head, F, is applied, by a sliding collar, F², which collar and head are acted upon by a spring, s, bearing against a fixed flange, t, and coiled around the collar and tube, as clearly shown in figs. 1, 2, and 4.

The spring s will press the upper end of collar F² up against the bottom of a platen, G, which is permanently secured to the upper end of tube E, as shown in fig. 2, and which may be partly covered on top by a piece of rubber, or other suitable yielding substance.

The head F is constructed with guides w, which leave between them and the flat surface of the platen G, a space for receiving one ticket at a time over the upper end of tube E, and allowing the ticket to be pressed against a gauge-lip, l, formed on the head F, as shown in fig. 4.

H is a cylindrical punch, which is secured to a plate, o, of the movable head F, so that its axis coincides with the axis of the tube E, and which may have its lower cutting-end bevelled, so as to cut more readily than it would if made square.

By the bevelling of the punch, as shown in fig. 4, it will make a clean cut by a drawing action.

The edge of the bore of the tube E, against which the cutting is performed, may be faced with a steel ring of less diameter than this bore, so that the edge will not be readily dulled, and also so that the punchings will be of less diameter than the inner diameter of said tube, and will not clog therein.

The punch-head is provided with a sliding top, F¹, which covers the plate o, and serves as an abutment for types n, which are inserted into a suitable recess formed in the head F over the platen G, and which are locked in said recess by a thumb-screw, s¹.

Types n are arranged on the opposite side of the punch H to the gauge-lip l, and are designed for dating tickets in the act of punching holes through them to cancel them.

In conjunction with types n, a ribbon, treated with

coloring-matter, is used, and arranged as indicated by the red line in fig. 4.

This ribbon is wound upon the shafts *i* of milled thumb-wheels *j*.

The spring *s* will keep the punch in position for receiving beneath it a ticket.

The cap or sliding top *F* affords a flat surface upon which to press the punch through a ticket, and allows access to types *n*, for readily changing them from time to time.

The tickets which I shall adopt, will have printed upon them, besides the names and numbers of stations upon a given road or route, their respective values, and also certain consecutive numbers indicating their order of arrangement in their respective cells in case *A*.

The consecutive numbers and price-mark will be printed near one end of each ticket, within a space of less diameter than the punch *H*, so that when a ticket is cancelled, by punching it as above described, the piece punched out will have printed upon it the price-mark and number of the ticket, and will be received in the tube *E*, for inspection by the proper officer, and a comparison by him with the tickets which are found in the case *A*.

The dating-stamp will render the ticket useless for any other trip.

When the case needs replenishing with tickets, it is unlocked by the proper officer, and the tickets are inserted into their respective cells from behind the face *A* and between the followers *K*, and the remaining number of tickets in the cells, in the order in which they are to be drawn.

When every cell in the case is filled, it is again locked and delivered to the conductor. The tickets being all numbered and arranged in the order in which they are to be drawn, and a record thereof made, with the value of the same, a comparison of the case, at the end of the return trip, will exhibit accurately the number of tickets which have been drawn from the case, and the value of the same, thus rendering it impossible for a conductor to defraud the company by false returns, without the fear of detection.

Having described my invention, What I claim as new, and desire to secure by Letters Patent, is—

1. A portable cellular ticket-case, *A A' B*, provided with an arm-ring, *C*, and a handle, *D E*, constructed substantially as described.

2. The arrangement, within a case, *A*, having a slotted face, *A'*, and a hinged or movable back, *B*, of a number of ticket-cells, each one of which contains a ticket-extractor, *J*, and a stop, *e*, substantially as described.

3. A cellular ticket-case, constructed with a slotted face, *A'*, and with a space, *N*, between the rear ends of the cells and a ribbed back, *B*, substantially as described.

4. The combination of a cellular ticket-case with a punch and a receptacle for the punchings, substantially as described.

5. A cancelling-punch, *H*, applied to spring-head *F*, in combination with a receptacle, *E*, and a locking-device therefor, substantially as described.

6. A cancelling-punch, *H*, and dating-types *n*, applied to a spring-head, *F*, and combined with a receptacle, *E*, and a locking-device, substantially as described.

7. The division-slide *d*, in combination with a punching-device and a receptacle for the punchings, substantially as described.

8. An extractor, *J*, constructed with tines upon its front end, substantially as and for the purposes described.

9. Notching the hooked ends of the extractors, substantially as and for the purposes described.

10. The stops *e*, upon the bottoms of the ticket-cells, in combination with extractors having tines deformed on their front ends, substantially as described.

EDWIN COWLES.
